WALL CONSTRUCTION

Filed Oct. 23, 1919

INVENTOR

J. F. C. LYNCH

BY

Milton S. Grindall,
ATTORNEY

UNITED STATES PATENT OFFICE.

JAMES F. C. LYNCH, OF SIOUX CITY, IOWA.

WALL CONSTRUCTION.

Application filed October 23, 1919. Serial No. 332,809.

To all whom it may concern:

Be it known that I, JAMES F. C. LYNCH, a citizen of the United States, and a resident of Sioux City, in the county of Woodbury 5 and State of Iowa, have invented certain new and useful Improvements in Wall Constructions, of which the following is a specification.

The primary objects of my present invention are: First, the production of a wall or ceiling embodying adjacent plastic coats between which there is no natural bond and material interposed between the coats to which such coats firmly adhere or bond and 15 which permits an unequal expansion and contraction of the coating materials without evil results; second, the production in such a construction or process wherein the material interposed between the coats, serves 20 not only as a perfect bond between the materials, but also renders the construction moisture proof and frost proof.

Much difficulty has been encountered in the production of a suitable bond for such 25 construction which will permit unequal expansion and contraction of the materials and which will render the structure frost proof and moisture proof. As far as I am aware, none of the bonds previously presented, are 30 practical and satisfactory.

I have attained the above and other objects and advantages, all of which will be readily understand and appreciated from the following disclosure, reference being had to 35 the accompanying drawing, which forms a part of this application and which is a fragmentary vertical section of a wall constructed in accordance with the invention.

In the embodiment illustrated, 1, is the plastic coat, the support for which may consist of the lath, 2, carried by studding, 3. The said plastic coat consists of gypsum plaster, so-called patent plaster, or any hard-setting plaster. After the plaster is applied and while it is in a plastic state, I apply 40 thereto a fibrous sheet, preferably tarred paper, 4, and to the outer surface of said sheet, I apply the coat of cement, 5. Other tarred sheets may serve successfully as a bond, but I prefer the use of tarred paper, 50 as it serves as a perfect bond and is impervious to moisture and a non-conductor of heat and cold.

The cement coating provides a hard, waterproof and weatherproof surface adapted to 55 receive a variety of finishes, and perfectly bonded to the plaster, and also providing a wall construction the cost of which is considerably less than when entirely composed of cement. 60

Another advantage which arises from the invention, is the fact that an impervious and frost proof plaster wall may be constructed by interposing between layers of plaster, the 65 tarred sheet.

Having thus described my invention, what I claim as new and desire to secure by Letters Patent of the United States, is,—

A construction comprising a layer of plaster, a layer of cement, and tarred paper interposed between the layers. 70

In testimony whereof I have hereunto set my hand this 8th day of September, 1919.

JAMES F. C. LYNCH.
